ATTORNEY

UNITED STATES PATENT OFFICE.

EMIL FURST, OF NEW YORK, N. Y.

DESIGN FOR A SIPHON-BOTTLE TOP.

54,251.

Specification for Design.

Patented Dec. 9, 1919.

Application filed January 9, 1919. Serial No. 270,430. Term of patent 7 years.

To all whom it may concern:

Be it known that I, EMIL FURST, a citizen of the United States, residing at New York, in the county of New York and State of New York, have invented a new, original, and ornamental Design for Siphon-Bottle Tops, of which the following is a specification, reference being had to the accompanying drawing forming a part thereof.

The following is a side view of a siphon bottle top, showing my new design.

I claim:

The ornamental design for a siphon bottle top, as shown.

EMIL FURST.
